(57) **CLAIM**

The ornamental design for an automatic air pump for traction device for orthopedic purpose, as shown and described.

DESCRIPTION

FIG. 1 is a front perspective view of an automatic air pump for traction device for orthopedic purpose;

FIG. 2 is a front elevation view of the automatic air pump for traction device for orthopedic purpose of FIG. 1;

FIG. 3 is a rear elevation view of the automatic air pump for traction device for orthopedic purpose of FIG. 1;

FIG. 4 is a left side view of the automatic air pump for traction device for orthopedic purpose of FIG. 1;

FIG. 5 is a right side view of the automatic air pump for traction device for orthopedic purpose of FIG. 1;

FIG. 6 is a top plan view of the automatic air pump for traction device for orthopedic purpose of FIG. 1; and,

FIG. 7 is a bottom plan view of the automatic air pump for traction device for orthopedic purpose of FIG. 1.
